(57) **CLAIM**

The ornamental design for a motor vehicle body and/or replica, as shown and described.

DESCRIPTION

FIG. 1 is a left, front perspective view of a motor vehicle body and/or replica showing our new design;

FIG. 2 is a left, rear perspective view thereof;

FIG. 3 is a front elevational view thereof;

FIG. 4 is a rear elevational view thereof;

FIG. 5 is a right side elevational view thereof, the left side being a mirror image thereof; and,

FIG. 6 is a top plan view thereof.

The bottom portion of the design is not being claimed. The broken lines shown throughout the drawing views are for environmental and illustrative purposes that form no part of the claimed design.
